UNITED STATES PATENT OFFICE.

MICHEAL A. GRINER, OF TALLYRAND, IOWA.

ATTACHMENT FOR CORN-PLANTERS.

SPECIFICATION forming part of Letters Patent No. 372,671, dated November 8, 1887.

Application filed May 17, 1887. Serial No. 238,546. (No model.)

To all whom it may concern:

Be it known that I, MICHEAL A. GRINER, of Tallyrand, in the county of Keokuk and State of Iowa, have invented a certain new and 5 useful Improvement in Attachments for Corn-Planters; and I do hereby declare the following to be a full, clear, and exact description of the invention, such as will enable others skilled in the art to which it appertains to make and 10 use the same.

My invention relates to an improvement in check-rowers for corn-planters.

The object is to provide a simple, effective, and inexpensive attachment which may be applied to any of the corn-planters in common 15 use with but slight change in their working mechanism.

With these ends in view my invention consists in certain features of construction and 20 combinations of parts, as will be hereinafter fully described, and pointed out in the claims.

In the accompanying drawings, Figure 1 is a bottom plan view of my improved check-rower attachment. Fig. 2 is a vertical section 25 on line $x x$ of Fig. 1. Fig. 3 is an end elevation.

A represents the main support of the frame, having rigidly secured to its ends at right angles the end bars, B B', which are suitably 30 braced in position by the rods a . Located on the main support A are the brackets b , as a means whereby the attachment is secured to a planter. Forwardly-projecting arms C C', parallel with each other and somewhat separated, are affixed to the main support A of 35 the frame near its center, and journaled in bearings c in their outer ends is a rotary shaft, D, on which is affixed, in position between the arms C C', a wheel or hub, E. This wheel or hub E is provided on both 40 ends with lateral flanges $d d'$, to which are secured, respectively, cam-blocks $e e'$, alternating with each other, so as to form between them and the flanges a serpentine groove, 45 f . An upright, F, projects vertically from the main support A opposite the wheel or hub E, its forward face preferably extending flush with said main support, and pivoted to this upright there is a lever, G, the lower end of 50 which is provided with a forwardly-projected anti-friction roller which rests normally in the

groove f , the lever being operated by the cams forming the groove. The upper or free end of the lever G is provided with several perforations, g , and loosely secured in one of said 55 perforations at a time is a link or arm, H, which connects either directly or indirectly with the seed-slide (not shown) of the grain-hopper. By placing the arm or link H in the lower of the perforations the extent of opening of the ports is lessened, and by placing it in the upper of the perforations the openings of the ports are increased. The shaft D is further supported in boxes h on the end bars, B B', and rigidly secured on each end of the 60 shaft D, outside of the end bars, B B', are ratchet-wheels K, said wheels having four teeth, or a number of teeth, to correspond with the cam-blocks on the wheel or hub E.

Latches L are loosely mounted on the ends 70 of the shaft D, so as to straddle the ratchet-wheels K. In the slotted end of the latches pawls l are pivoted, so as to normally engage with the teeth of the ratchet-wheels. These latches L are provided with outwardly-extending 75 forks m at their lower end, and a spiral spring, n , normally holds the latches forward, while gravity-pawls T normally engage the teeth of the ratchet-wheels, preventing a retrograde movement of the shaft.

Brackets M project laterally from the rear end of the end bars, B B', and consist, essentially, of parallel plates $m' m^2$, each of which has a rearwardly-projected lower end or horn, m^2 . The construction of these plates is such 85 that plate m' is considerably broader and extends considerably lower than plate m^2 . A pulley, n' , is loosely mounted on a short shaft, n^2 , affixed in the lower end of plate m' , and a second pulley, o , somewhat wider than pulley n' , is located slightly above and forward of the latter and journaled in the plates. Both pulleys have a grooved periphery and a space remaining between the end of plate m^2 and pulley n' for the passage of the tappet-wire when 90 removing it from the planter or attaching it thereto.

Arms O project laterally from the forward ends of bars B B', and extending from their outer ends are pulleys p , also having grooved 100 peripheries. Guide-pulleys P, extending from brackets p^2 , hold the tappet-wire in contact

with these pulleys *p*. These pulleys all serve as guides for the tappets *Q* on the tappet-wire *R*, which, by passing between the pulleys and engaging the latches with the tappets, operates the discharge of grain at intervals from the hoppers.

It is evident that slight changes might be resorted to in the form and arrangement of the several parts described without departing from the spirit and scope of my invention; hence I do not wish to limit myself to the particular construction herein set forth; but,

Having fully described my invention, what I claim as new, and desire to secure by Letters Patent, is—

1. The combination, with a rotary shaft carrying a wheel having a cam-groove thereon, and a pivoted lever having an anti-friction roller adapted to operate in said cam-groove, of the ratchet-wheels rigidly secured on the shaft, latches loosely mounted on the shaft and spanning the ratchet-wheels, and guide pulleys, one set of which are mounted in brackets, the other

set being mounted between a pair of parallel outwardly-turned plates, one of said plates terminating in a horn a short distance from the axis of the outer pulley.

2. In a check-rower for corn-planters, the combination, with a supporting frame, of guide-pulleys, one set of which are mounted in brackets, consisting, essentially, of a pair of parallel outwardly-turned plates, the pulleys being mounted between these plates, and one plate terminating in a horn a short distance from the axis of the outer pulley, and the other set on a depending bracket, one pulley mounted vertically thereon and the other horizontally, substantially as set forth.

In testimony whereof I have signed this specification in the presence of two subscribing witnesses.

MICHEAL A. GRINER.
